UNITED STATES PATENT OFFICE

2,182,105

INTERNAL COMBUSTION ENGINE CYLINDER-HEAD CONSTRUCTION

Arthur A. Woodward, Detroit, Mich., assignor to
Skinner Motors, Inc., Detroit, Mich., a corporation of Delaware

Application September 19, 1938, Serial No. 230,611

9 Claims. (Cl. 123—173)

The current invention pertains to certain features of betterment and refinement in internal combustion engines of the character and type presented in United States Letters Patent No. 1,830,136, R. L. Skinner, Internal combustion engines, granted November 3, 1931, the invention relating more particularly to improvements in the cylinder-head and the parts of the mechanism with which it cooperates.

10 One object of the invention is to provide a different, simpler, and more economical spring means coacting with the cylinder-head for maintaining the hold-down ring yieldingly pressing down against the ported, split, expandible sealing-ring.

15 A further aim of the invention is a novel mounting of the cylinder-head in the cylinder, whereby to overcome certain difficulties encountered in constructions wherein the cylinder-head is held in place by studs and nuts or cap-screws.

20 An additional purpose of the invention is to mount the flexible, pressure-sealing reeds in a more effective, less expensive and simpler manner than has heretofore been feasible.

25 To enable those trained in this art to understand the present invention both from structural and functional standpoints, a present, preferred embodiment of the invention has been illustrated in detail in the accompanying drawing, the single view of which is a fragmentary, central, vertical section through one cylinder of a multi-cylinder internal-combustion engine incorporating the new structural features.

30 Referring to this drawing, it will be perceived that the engine or motor illustrated therein has an outer, water-jacketed cylinder 11 with intake and exhaust ports 12 and 13, respectively, a shorter, inner cylinder 14 inside of, concentric with and spaced inwardly from, such outer cylinder, thus providing an annular space between the two cylinders, such inner cylinder terminating below the ports of the outer cylinder.

35 Above such inner cylinder and resting on the upper edge thereof is the usual, split, expandible, ported sealing-ring 15 having its ports in register with those of the outer cylinder.

40 Bearing on top of such sealing-ring 15 is the customary, continuous or unsplit and hence non-expandible hold-down ring 16 having a narrow, inwardly directed flange along its lower edge, whereby the gas pressure in the cylinders may act thereon to force the hold-down ring downwardly.

45 Slidable lengthwise between the outer cylinder 11, on the one hand, and the inner cylinder 14,

5 sealing-ring 15 and hold-down ring 16, on the other hand, are the well-known, thin, substantially semicircular, ported valves 17 and 18 governing and controlling the opening and closing of the registered ports of the outer cylinder and the sealing-ring, these valves being reciprocated in proper timed relationship by means, not shown, because the United States Letters Patent referred to above, to which reference should be had, fully disclose these and other associated means.

10 The engine, of course, has a piston reciprocating in the internal cylinder coupled to the engine crank-shaft by a connecting-rod, but none of these parts are shown in the drawing as their illustration is not essential to an understanding of the present invention.

15 The cylinder-head 19, instead of being held in place on the cylinder-block or casting by the customary plurality of circularly spaced studs and nuts or cap-screws is fastened in position by much simpler and effective novel means.

20 As is shown, the upper part of the interior of the outer cylinder has a circular groove 21 therein of larger diameter than the bore of the cylinder, and the top portion of the cylinder-head has a circular, upwardly-facing shoulder 22 and between such shoulder and the upper surface of the cylinder-groove there is interposed a soft or resilient gasket 23 such as rubber or any other 25 suitable material, and on top of that is a split, metal, expandible locking or retaining ring 24 which secures the cylinder-head firmly in place by being of such width as illustrated to overlie 30 the cylinder-head shoulder.

35 To assemble these parts, the cylinder-head is inserted in the cylinder a sufficient distance to allow the introduction of the gasket and locking-ring into register with the groove 21, whereupon they both expand into the groove while at the same time overlapping the cylinder-head shoulder.

40 The cylinder-head is thus prevented from ascending under the upwardly acting forces of the explosions in the cylinders, such forces being cushioned by the gasket from detrimentally reaching the cylinder-block.

45 The manner of demounting the cylinder-head will be readily understood by any one skilled in this art.

50 This construction has at least two outstanding advantages over the prior art structure.

55 The fault in the earlier art has been that the cylinder-heads, which are normally subjected to high loads, are held in place at several separated

points by threaded studs and their nuts or cap-screws and the forces or loads acting on the cylinder-head are distributed by it to these diverse points of attachment causing the latter to distort the cylinder-block in a manner to disturb or vary the cylindrical shapes of the engine-cylinders making them slightly tapered or out-of-round or both.

In the present new construction, any upward pressure on the cylinder-head caused by the gas pressure is transmitted from the cylinder-head through the gasket to the confining or locking ring and from the latter directly and circumferentially equally to the cylinder-casting around its bore, thus creating merely an unobjectionable tendency to stretch or elongate the cylinder longitudinally uniformly at all points without distortion of the cylinder-bore.

Again, the current novel structure materially reduces the cost of manufacture in that it eliminates the necessity for employing and installing the numerous studs and their nuts or alternatively the cap-screws.

In addition, the employment of the new construction provides a simple and facile method of installing and removing the cylinder-heads from the engine.

As is fully illustrated, the cylinder-head has a medial, circumferential recess 25 with a downwardly facing circular shoulder 26 against which bears the inner portion of a relatively-flat washer-shaped, endless spring 27, the outer, circular, marginal part of such spring overlying and bearing on the upper edge of the hold-down ring 16, the arrangement and disposition of parts being such that as the hold-down ring tends to rise, due at least in part to the upward travel of the valves, such ascent is yieldingly resisted by the action of the spring, the thickness of which and the amount of its deflection from its flat condition determining the load which it imposes on the hold-down ring and through that on the sealing-ring.

Among the valuable advantages which this design incorporates over that set forth in the specified patent may be mentioned the following, the new structure (a) involves the use of the least number of parts, (b) avoids the employment of a number of comparatively-short helical-springs, (c) escapes the need for any member acted upon by such spiral-springs to distribute their conjoint actions on the hold-down ring, (d) the new annular type of spring is so constructed that its radial position is closely controlled by the cylinder-head around which the spring is fitted (e) the relative ease of assembly of the cylinder-head unit embodying this type of single, flat spring as compared with the assembly problem of a head using the required multiple, small helical-springs to develop the needed axial load, and (f) the resisting force of the one, new, simple spring increases steadily as the deflection is augmented, thus insuring that any tendency of the hold-down ring to rise above its normal position will be opposed by an increasing axial load offered by the spring.

The new and improved cylinder-head construction also includes another important feature in that, heretofore, nested, resilient, tapered, metallic reeds engaging the inner face of the hold-down ring at their peripheries have been mounted on the cylinder-head by being clamped between a pair of holders carried by the head, but, in the present improved appliance, such reeds 28 have their inner parts held in the head by placing them

in the mold and then casting the cylinder-head around them, whereby the metal of the head anchors the inner portions of the reeds firmly and securely in place, thus avoiding the need for any additional or separate reed-clamping part or parts.

All of the associated, hereinbefore-mentioned mechanical elements act to seal the gas pressures in the cylinders, the reeds preventing such pressures from escaping up inside of the hold-down ring, the spring 27 forcing the hold-down ring down on to the sealing-ring 15 precluding rise of the latter from the top end of the inner cylinder and hence avoiding loss of pressure at this point, the gasket 23 and the retaining ring 24 barring loss of pressure at the top of the cylinder.

Thus all of the new structural characteristics detailed above conjointly contribute to the adequate retention of gas pressures in the cylinders.

Those skilled in this art will understand that the invention as defined by the appended claims, which should be interpreted as generically as permitted by the prior art, is not necessarily limited and restricted to the precise and exact details of structure shown and described and that the appliance herein set forth may be modified within proper limits without departure from the heart and essence of the invention and without the loss or sacrifice of any of its material benefits and advantages.

If desired, the inner side-wall of the cylinder-groove 21, as shown in the drawing, may be made oblique or bevelled to facilitate the removal of the cylinder-head by contracting the locking-ring and its gasket upon temporary forcing of the cylinder-head inwardly of the cylinder to allow similar inward movement of the ring and gasket to effect their contraction to allow their removal.

I claim:

1. In an internal combustion engine, the combination of an outer cylinder having port-means, a shorter inner cylinder inside of, concentric with, and spaced inwardly from said outer cylinder and terminating at one end short of the port-means of said outer cylinder, a split expandible sealing-ring bearing at its inner end on said end of said inner cylinder and having port-means registering with said port-means of said outer cylinder, a continuous hold-down ring bearing at its inner end on the opposite end of said sealing-ring, a cylinder-head mounted on said outer cylinder and having an inwardly facing circumferential shoulder, an endless washer-shaped spring substantially flat when not under strain, surrounding said cylinder-head and having a shifting bearing at its inner portion solely on said cylinder-head shoulder and also having a shifting bearing at its outer portion directly on the outer end of said hold-down ring and under strain yieldingly maintaining said hold-down ring in longitudinal position and said sealing-ring against said end of said inner cylinder, a reciprocatory curved valve-means slidable lengthwise in the space between said cylinders and opening and closing the registered port-means of said outer cylinder and of said hold-down ring.

2. In an internal combustion engine, the combination of an outer cylinder having port-means, a shorter inner cylinder inside of, concentric with, and spaced inwardly from said outer cylinder and terminating at one end short of the port-means of said outer cylinder, a split, expandible sealing-ring bearing at its inner end on said end of said inner cylinder and having port-means registering with said port-means of said outer

- cylinder, an endless hold-down ring bearing at its inner end on the opposite end of said sealing-ring, a cast-metal cylinder-head mounted in said outer cylinder, means yieldingly pressing said hold-down ring down on said sealing-ring, curved valve-means slideable lengthwise in the space between said cylinders and opening and closing the registered port-means of said outer cylinder and of said hold-down ring, and nested, tapered, 10 open-center, round metal reeds cast in said cylinder-head and projecting from said cylinder-head and engaging the inner face of said hold-down ring in gas-pressure confining relation.
3. In an internal-combustion engine, the combination of a cylinder having an internal circumferential groove near one end of said cylinder and of larger diameter than the bore of the cylinder, a cylinder-head fitted in said end of said cylinder and having an outwardly facing circumferential shoulder, and an expandible and contractible snap locking-ring occupying said groove and overlapping said shoulder thereby confining said head in said cylinder.
4. The structure presented in claim 3 in combination with a gasket also occupying said groove and in engagement with said ring.
5. The structure presented in claim 3 in combination with a gasket interposed between said cylinder-head shoulder and said locking-ring.
- 30 6. The structure presented in claim 3 in combination with a gasket occupying said groove and interposed between said cylinder-head shoulder and said locking-ring.
7. The structure presented in claim 3 in which said locking-ring engages the outer side-wall of said groove, in combination with a gasket also occupying said groove, engaging the inner side face of said ring and overlapping and engaging said cylinder-head shoulder.
8. The structure presented in claim 1 in which said cylinder has an internal circumferential groove near one end of said cylinder and of larger diameter than the bore of the cylinder, in which said cylinder-head is fitted in said end of said cylinder and has an outwardly facing circumferential shoulder, in combination with an expandible and contractible snap locking-ring occupying said groove and overlapping said shoulder thereby confining said head in said cylinder.
9. The structure presented in claim 2 in which said cylinder has an internal circumferential groove near one end of said cylinder and of larger diameter than the bore of the cylinder, and in which said cylinder-head has an outwardly-facing circumferential shoulder, in combination with an expandible and contractible snap locking-ring occupying said groove and overlapping said shoulder thereby confining said head in said cylinder.

ARTHUR A. WOODWARD. 30
